IMPACT-FUSE.

1,072,546.

Specification of Letters Patent.

Patented, August 9, 1913.

Application filed December 31, 1912. Serial No. 733,561.

To all whom it may concern:

Be it known that I, KARL WIESER, residing at Bredeney, Germany, a subject of the Emperor of Germany, have invented a certain new and useful Improvement in Impact-Fuses, of which the following is a specification.

This invention relates to impact fuses which are adapted to operate with or without retardation, and the subject matter of this invention is a fuse of this kind, which works automatically with perfect safety with or without retardation depending on whether the violence of the impact is greater or smaller.

In the accompanying drawing is illustrated one embodiment of the present invention representing a base fuse; and Figure 1 shows a longitudinal section of the fuse; Fig. 2 a similar section to Fig. 1 with different positions of the parts; and Fig. 3 a section on line 3—3 of Fig. 1 seen from above.

The fuse housing A is provided with a hammer B containing a fulminate b¹ which hammer is secured against displacement by means of a safety C, of well known construction, actuated by centrifugal force. In front of the hammer B is situated a firing pin a² in a partition a¹ of the fuse housing A, against the front face of this partition a¹, remote from the hammer, a second hammer D is resting, which may be displaced in the same direction as the hammer B, said hammer D being secured against displacement by means of a compressible ring E. In the middle of the hammer D is provided a passage d¹ running in an axial direction and opening into the ring E. This passage communicates on the one hand, by means of several borings a³ in the partition a¹, with the chamber wherein the ignition flame is generated; and on the other hand said passage communicates with the impact charge F, which is situated in the closing plug a⁴, by means of several borings a⁵ provided in the closing plug a⁴ of the fuse housing.

The strength of the ring E is calculated so that it cannot be compressed to any visible extent by the hammer D, on the impact of the projectile against a body of small resistance; but which ring upon impact of the projectile against a target of great resistance, for instance armor plate, will be so far compressed that the passage d¹ of the hammer D may be closed by a valve cone a⁶ situated in the closing plug a⁴, see Fig. 2. From

the passage d¹ a second passage a⁷ branches off, which latter runs in a zig-zag direction as shown in the drawing, and opens into the free chamber situated outside the ring E between the hammer D and the closing plug a⁴, which chamber is connected with the impact charge F through passage a⁷.

Should the projectile hit a target of small resistance, the hammer B will evidently be shot forward while the hammer D, as a consequence of the resistance of the ring E practically remains in its original position. The ignition flame will then arrive through the path a³ d¹ a⁵ directly to the impact charge, and the ignition then takes place without any retardation whatever. Should, on the other hand, the projectile hit a target of great resistance, the hammer D will be shot so far forward on account of the violent impact and overcoming resistance of the ring E, that the passage d¹ will be closed by the valve cone a⁶. The ignition flame will thereupon be compelled to take its course through the zig-zag shaped passage a⁷ and will arrive through this and the passage a⁷ to the impact charge. The ignition will therefore take place in well known manner with retardation. It has then been attained by means of this described arrangement that the fuse without any manual adjustment whatever, and with complete safety, automatically operates without retardation in that case when a subsequent explosion of the projectile on impact is desired; but operates with retardation in that case wherein a retardation of the ignition is desired, for instance on firing against armor plate.

I claim:

1. An impact fuse having a detonating charge and a fulminate a hammer inserted between the two, a direct passage and a circuitous passage in said hammer, and means for closing said direct passage actuated by the impact of the projectile with a target of great resistance.

2. An impact fuse having a detonating charge and a fulminate, a hammer inserted between the two, a direct passage and a circuitous passage in said hammer, a collapsible member retaining said hammer in its original position, and a cone adapted to close said direct passage on the impact of the projectile with a target of great resistance, whereby a flame from the fulminate is compelled to follow the circuitous passage to the detonating charge.

3. An impact fuse comprising a housing with two chambers divided by a partition, a hammer in one of said chambers, normally situated at the rear of said chamber, and a member for retaining said hammer in said position on impact with a target of slight resistance; said member being distorted by the inertia of said hammer on impact against a target of great resistance; a detonating charge inclosed in a hollow part of the housing adjacent the forward end of the forward chamber, a fulminate in the second chamber and means for igniting the fulminate on impact, passages through said partition, said hammer, said member and the wall of said housing, permitting a direct course from the second chamber to said detonating charge for the flame generated in said second chamber on a slight impact of the projectile.

4. In an impact fuse, having an automatically selected delayed action device, comprising a housing with two chambers divided by a partition, a fulminate and means for igniting said fulminate on impact in the first chamber, a hammer in the second chamber, a detonating charge inclosed in a hollow part of said housing, a collapsible member normally and on slight impact retaining said hammer at the rear of said second chamber, said member collapsing from the inertia of said hammer on impact against a target of great resistance; a direct passage in said hammer from said first chamber to said detonating charge; a circuitous duct in said hammer and a port registering therewith leading to said detonating charge, a valve cone constructed to close said passage on the collapse of said member, whereby the flame from the fulminate will be compelled to take a longer course to reach the detonating charge and delayed action will follow.

5. An impact fuse comprising a housing with two chambers situated one behind the other and divided by a partition, a hammer in the forward chamber, normally situated at the rear of said chamber, and a member for retaining said hammer in said position on impact with a target of slight resistance, said member being distorted by the inertia of said hammer on impact against a target of great resistance; a detonating charge inclosed in a hollow part of the housing adjacent the forward end of the forward chamber, a fulminate in the second chamber and means for igniting the fulminate on impact, passages through said partition, said hammer, said member and the wall of said housing, permitting a direct course from the second chamber to said detonating charge for the flame generated in said second chamber on a slight impact of the projectile.

6. An impact fuse comprising a housing with two chambers situated one behind the

other and divided by a partition, a hammer in the forward chamber, normally situated at the rear of said chamber, and a member for retaining said hammer in said position on impact with a target of slight resistance, 70 said member being distorted by the inertia of said hammer on impact against a target of great resistance; a detonating charge inclosed in a hollow part of the housing adjacent the forward end of the forward chamber, a fulminate in the second chamber and means for igniting the fulminate on impact, a direct passage and a circuitous passage in said hammer; a collapsible member retaining said hammer in its original position, and a cone adapted to close said direct passage on the impact of the projectile with a target of great resistance, whereby a flame from the fulminate is compelled to follow the circuitous passage to the detonating charge, on 80 impact of the projectile with a target of great resistance causing delayed action; and whereby a flame from the fulminate will follow the direct passage to the detonating charge on impact of the projectile with a 90 target of slight resistance causing direct action.

7. In an impact fuse capable of acting with or without retardation, a movable part adapted to assume either a position in which the fuse will act with retardation or a position in which no retardation will follow, a housing having a solid abutment, and a yielding member interposed between said movable part and said abutment, said yielding member, according to the violence of the impact, being adapted either to retain said movable part in its original position, in which the fuse will act without retardation or to allow the movable part to pass into a 100 position in which the action of the fuse will take place with retardation.

8. In an impact fuse capable of acting with or without retardation, a movable part adapted to assume either a position in which the fuse will act with retardation or a position in which no retardation will follow, a housing having a solid abutment, and a yielding member interposed between said movable part and said abutment, said yielding member, according to the violence of the impact, being adapted either to hold said movable part in a position, in which the fuse will act without retardation or to allow said movable part to pass into a position, in 120 which the action of the fuse will take place with retardation.

9. In an impact fuse capable of acting with or without retardation, a movable part adapted to assume either a position in which the fuse will act with retardation or a position in which no retardation will follow, said movable part being in the form of a percussion hammer, a housing having a solid abutment, and a yielding member interposed 130

between said hammer and said abutment, said yielding member, according to the violence of the impact, being adapted either to hold said hammer in a position, in which the 5 fuse will act without retardation or to allow said movable part to pass into a position, in which the action of the fuse will take place with retardation.

The foregoing specification signed at Bar-
men, Germany, this 11th day of December, 1912.

KARL WIESER. [L. S.]

In presence of—

HELEN NUFER,
ALBERT NUFER.
